R. W. ROSE.
DUMPING VEHICLE HOIST.
APPLICATION FILED SEPT. 1, 1916.

1,226,384.

Patented May 15, 1917.

UNITED STATES PATENT OFFICE.

ROBERT W. ROSE, OF MARBLEHEAD, MASSACHUSETTS.

DUMPING-VEHICLE HOIST.

1,226,384.

Specification of Letters Patent.

Patented May 15, 1917.

Application filed September 1, 1916. Serial No. 118,022.

To all whom it may concern:

Be it known that I, ROBERT W. ROSE, a citizen of the United States, and resident of Marblehead, in the county of Essex and 5 State of Massachusetts, have invented an Improvement in Dumping-Vehicle Hoists, of which the following description, in connection with the accompanying drawings, is a specification, like letters on the drawings 10 representing like parts.

My present invention is an improved hoisting apparatus for vehicles, especially intended for use in elevating heavy loads of automobile coal trucks or the like handling 15 heavy articles in bulk. Hoisting mechanism for such vehicles requires a very powerful and efficient mechanical construction which will also secure a relatively high tilting or elevation in order to unload completely and 20 quickly and also have a relatively low center of gravity. It will be appreciated that a five-ton load, for example, if supported at a considerable distance above the chassis of an automobile, could not be raised for un- 25 loading on a side hill, or other inclination, without danger of upsetting the vehicle or throwing undue strains thereupon. Heretofore complex mechanism has been expensive to install and maintain, and the object of 30 my present invention is to improve, simplify and perfect such hoisting mechanism and to enable a powerful, quick acting, strong, hoisting mechanism to work within a very short vertical compass between chassis and 35 vehicle body, giving low center of gravity and also great power at the beginning of the hoisting action. A still further feature of the present hoist is the provision of a novel form of hoisting levers or bars which will 40 extend forwardly at either side of and entirely clear from the transmission or other motor mechanism of the chassis, thus enabling a very long body and great length of 45 hoisting levers to be carried. In carrying out the invention I prefer to utilize a single length of hoisting member which is somewhat curved longitudinally, and to use cross braces spanning a segment of such curve, which gives great rigidity from torsional 50 strains of every description. I also prefer to form a portion of the hoisting levers with an inclined plane surface to operate at the beginning of the hoisting action and to make said hoisting levers entirely free from all 55 journal bearings, rolls, joints or the like, which multiplicity of rolls and parts is very

objectionable and expensive, and to use a simple, anti-friction bearing, fixed on the chassis over which the levers travel.

A further very important feature consists 60 in using the slow but powerful direct lift of the winding chains which operate the hoisting levers, to exert an extra vertical lift on the initial inclining or tilting of the body, and then, after the load is started upwardly 65 and the hoisting becomes easier, to use the faster action of the curved levers. To this end, the winding chains are so arranged that they will bear upon a suitable part of the hoisting mechanism, preferably being en- 70 gaged by a crossbar or similar bearing upon the curved levers, with the extreme outer ends of the chains attached to the corresponding outer ends of said levers. Thus a direct vertical lift is secured and then the 75 continued winding up of the chains automatically transfers the lifting power to the outer ends of said levers and a smooth continuous strain is held on the gears through which the power for hoisting is trans- 80 mitted.

Referring to the drawings illustrating a preferred embodiment of the invention, Figure 1 is a side view of my novel form of hoisting apparatus applied to an automobile 85 coal truck;

Fig. 2 is a plan view showing a portion of the dumping body broken away to illustrate the frame and hoisting construction underneath.

Fig. 1 illustrates in conventional form an automobile chassis, comprising the engine 1, sides of the chassis 2, driver's seat 3, and suitable transmission and running mechanism which need not be further illustrated 95 or included. Mounted on the rear portion of the chassis 2 are side frames 4, 4, supported on cross-beams 5. Two of these cross-beams at the forward end may be extended to the side frames 4 to carry a bar 6 supporting a gearing to operate the hoist. A rear cross member 7 unites the extreme ends of the frame 4. As illustrated in the drawings, I have shown the wagon body 8 considerably broader than the side frames 4 and 100 therefore overhanging the chassis and the wheels, said body being of any usual height or construction and built with cross members of angle iron or the like 9 which rest upon the sides 4 when in lowered position. This 105 body is pivoted at 10 to the rearmost portion of the frame, two or more pairs of iron

braces 11 and 12 being pivoted upon a shaft 13 on which the body swings. My novel form of hoisting levers are arranged at each side of the frame 4 and comprise curved arms 14. Each of these arms is of a single continuous piece of metal and is pivoted directly to the bottom of the body 8 at 15, said arm being formed with a short section, from 15 to 16, then with an inclined surface from 16 to 17 and then on the arc or other line from 17 to its extreme inner end 18. Near the pivoted end 15 is a short spur arm or link 19 having a cross rod 20 uniting the ends of said link 15 and a brace 21 also connecting same. The usual cross braces 22, 23, 24 and 25 are applied, substantially as shown. It will be appreciated that the utilization of such cross rods in substantially the position illustrated in the drawing gives immense strength and rigidity to the arc-like form of the hoisting apparatus, constituting braces in appropriate position to resist and withstand longitudinal, transverse and torsional strains from all directions. Where straight hoisting arms are employed, the usual cross braces only impart strength in the plane of the levers, but in the arrangement of my hoisting apparatus, the increased strength afforded will be appreciated. Furthermore, this arrangement leaves the inner end portions 18 free from cross braces, rods or the like and this enables the projecting ends of the hoisting arms in my apparatus to extend a considerable distance forwardly, which thus gives greater length to the arms 14 and consequently a greater capacity for height of hoisting and yet enables said arms to be entirely free from the transmission mechanism 26 or similar portions of the driving mechanism in the chassis. My present construction greatly simplifies the use of rolls or other bearing parts which require to be oiled, and I am enabled to have the hoisting arms entirely free from the necessity of carrying rollers, bearings or the like. To this end I provide a grooved anti-friction roller 27 journaled directly on the side frame 4 or over the chassis sides 2 in alinement with each hoisting arm 14, a common shaft 28 uniting these two grooved rollers. Said rollers and the inclined portion from 16 to 17 of each hoisting arm are, when the body is lowered, in proper position to secure the increased power afforded by the inclined surface from 16 to 17 during the initiation of the hoisting action, when the maximum power must be exerted, thus simplifying the gearing required. To operate the hoist arms, I provide a pair of chains 30 having the inner end link held by a pin passing through the bent-over end of the bar 14 as shown at 31, and the other end secured to a shaft 32, about which shaft said

chains are wound through rotation of the gears 33, 34, 35 and 36, the latter being fitted with a handle 37 to be manually rotated, a frame and guard 38 therefor being provided as usual. Each chain 30 is led under the cross bar 20 uniting the ends of the short links 19. Therefore, in the operation of the hoist apparatus the first rotative movement of the shaft 32 winding up said chains 30, will exert a direct lifting tension on the cross-beam 20, as well as a lateral tension on the ends 18 of each link, thus imparting a forward movement thereto and also raising the body 8 through the sliding action of the inclined portion from 16 to 17 of each arm on the grooved roller 27. As the body is partially lifted, the end 18 of each arm 14 swings downwardly, forcing the arms 14 into contact with the grooved rollers 27 during the continued winding of the chains 30. The curve of the arm 14 may be so formed as to increase the speed proportionately to the lifting power required for the final operation of the hoisting mechanism, thus accelerating the elevation of the body 8. When the chain is entirely wound upon the shaft 32 and the body 8 lifted to the limit of its inclination, said chain and arms will also constitute a rigid, firm and automatic stop to limit the further tilting movement of the body 8, as the end of the chain will be completely wound on the shaft and the end-most link held at 31 to the end 18 of each arm, binds said arm securely to the shaft and vehicle. The last operation of the lifting action permits the arm 14 to slide free of the roller 27 and to rest directly upon the axle 32, but, at this stage, as the weight of the body 8 and its load is almost entirely thrown upon the pivot therefor at 10, there is comparatively little strain on the shaft 32, and no inconvenience results from this construction.

It will be readily appreciated that I have devised an extremely strong, rigid, simple and quick-acting hoisting arrangement, permitting great length of hoisting levers, affording a large increase of power at the initiation of the hoisting action and great speed at the completion of the same. Also that the formation of the hoisting levers 14 with combined circular and inclined plane faces constitutes a peculiar type of bent arm from which I obtain important results. I believe that this type of hoist, firmly pivoted to the body and free of rollers, etc., with a capacity for great power and speed, is an important improvement in this art, and therefore I wish to claim the same broadly. Also the long length of hoisting arms, which, though rigidly braced, have the inner ends entirely free and capable of clearing the running gear, transmission mechanism or parts of the motor of the chassis, are important features and

combine great advantages, permitting a long lever to secure great elevation and yet to be pivoted at the forward part of the body and are distinctly novel. The 5 short links 19 securing a straight initial lift from the chain 30 and at the completion of the hoisting action resting directly on the body 8, thus giving a firm four-point bearing thereon, also constitute an important 10 feature, and greatly strengthen the support for the body when it is in its highest inclined position.

While I have herein illustrated the hoist in a simple form, it will be appreciated 15 that I may utilize the same in connection with a rear elevating hoisting mechanism also, and, if desired, on turntable trucks or the like.

My invention is further described and 20 defined in the form of claims as follows:

1. Apparatus of the kind described, comprising a vehicle truck, a body mounted thereon with provision for lifting at an inclination, mechanism to lift and incline said 25 body with relation to the truck, said mechanism including a pair of hoisting levers arranged at each side of the body, a bearing for said levers intermediate their length over which said levers travel, flexible actuating means for said pair of levers attached to the outer ends of said levers and a bearing for the flexible winding means on said levers whereby the initial winding will exert 30 a vertical lifting tension on the levers and a vertical lifting tension on the levers and 35 said body, and then complete the lifting action by actuating said levers from their outer ends.

2. Apparatus of the kind described, comprising a vehicle truck, a body mounted 40 thereon, with provision for lifting at an inclination, and hoisting mechanism, including a pair of hoisting levers pivoted to the body and having inclined surfaces to cooperate with an anti-friction roller during 45 a portion of the hoisting action, and a bearing contour for said levers extending above the bottom of the body when in lowered position and adapted to also bear on said anti-friction roller during a portion of the 50 hoisting action.

3. Apparatus of the kind described, comprising a vehicle truck, a body adapted to be inclined thereon, a pair of curved hoisting levers pivoted to the body and having 55 cross braces extending adjacent each end across an arc of the levers, whereby a combined horizontal, vertical and torsional bracing is secured.

4. Apparatus of the kind described, comprising a vehicle truck, a body adapted to 60 be inclined thereon, a pair of curved hoist-

ing levers pivoted to said body at one end and having means to operate them secured to the opposite ends, anti-friction rollers carried by the truck for said levers to engage during the hoisting operation for the entire length of said levers and means permitting a further hoisting action to said levers after they have left the said rollers. 65

5. Apparatus of the kind described, comprising a vehicle truck, a body mounted thereon to be hoisted at an angle, hoisting mechanism therefor operating between the bottom of said body and the top of the truck, said mechanism including a pair of 75 curved arm levers, each lever having one end pivoted to the body and the other end free, an anti-friction bearing on said truck for each lever, the outer end of said levers normally extending above the plane of said 80 bearing, flexible means connected with the free ends of said levers and adapted to wind upon a shaft at the other side of said anti-friction bearings, a cross-bar on said curved levers normally below said anti-friction 85 bearing and in position to be engaged by the flexible winding means at a distance below the winding shaft therefor, whereby the winding of said flexible means will first exert a substantially vertical lifting action 90 on the hoisting levers and when the cross-bar is above the level of the winding shaft, will then transfer the lifting power of said flexible winding means to the outer ends of the hoisting levers to complete the hoisting 95 action.

6. Apparatus of the kind described, comprising a vehicle truck, a body adapted to be hoisted at an angle thereon, hoisting mechanism operable between the bottom of 100 said body and the top of the truck, said mechanism including a pair of curved arm levers, flexible winding means attached to the outer end of said levers, a spur arm from each curved lever, means on said spur arms 105 to contact with the flexible winding means, so arranged as to provide a substantially vertical lifting action on the body at the initiation of the hoisting action and thereafter to bear directly against the body at 110 the limit of its hoisting action, thereby providing a four-point bearing on said body and constituting a stop to limit said hoisting action.

In testimony whereof, I have signed my 115 name to this specification, in the presence of two subscribing witnesses.
